UNITED STATES PATENT OFFICE.

MAUD A. MOFFATT, OF DORCHESTER, MASSACHUSETTS.

DESIGN FOR A CANDY-BOX.

49,070.

Specification for Design.

Patented May 16, 1916.

Application filed March 22, 1916. Serial No. 86,003. Term of patent 3½ years.

To all whom it may concern:

Be it known that I, MAUD A. MOFFATT, a citizen of the United States, residing at Dorchester, in the county of Suffolk and State of Massachusetts, have invented a new, original, and ornamental Design for Candy-Boxes, of which the following is a specification, reference being had to the accompanying drawing, forming part thereof.

Figure 1 is a side elevation of the candy box, showing my new design. Fig. 2 is an edge elevation of the candy box, showing my new design.

I claim—

The ornamental design for a candy box, as shown.

MAUD A. MOFFATT.
